SEATING STRUCTURE

Frank Albach and George R. Chervenka, St. Louis,
Mo., assignors to Fred Medart Manufacturing
Company, St. Louis, Mo., a corporation of Mis-
souri

Application June 3, 1937, Serial No. 146,163

37 Claims. (Cl. 189—1)

This invention relates generally to seating-structures and, more particularly, to a certain new and useful improvement in seating-structures of the type commonly known as indoor bleachers for use in auditoriums, gymnasiums, and other enclosures.

Our present invention has for its primary object the provision of an indoor seating-structure of telescopic or foldable type, which may with ease, facility, and convenience be opened or closed, and which, when open, unfolded, or expanded, affords seating capacity for a relatively large number of individuals or spectators and, when closed or folded, occupies a comparatively small space.

Our invention has for a further object the provision of a seating-structure of the type stated, which may be readily constructed and installed, which is strong, rugged, durable, and economically maintained in service, and which is exceedingly efficient in the performance of its intended functions.

And with the above and other objects in view, our invention resides in the novel features of form, construction, arrangement, and combination of parts presently described and pointed out in the claims.

In the accompanying drawings, (four sheets), Figure 1 is a side vertical sectional view of a telescopic or foldable seating-structure or bleachers constructed in accordance with and embodying the present invention, the structure being shown in opened out or so-called unfolded condition;

Figure 2 is a side vertical sectional view of the structure in closed, telescoped, or folded condition;

Figure 3 is a front elevational view of the structure;

Figure 4 is an enlarged elevational detail view, partly broken away and in section, of one of the movable frame roller-carriages of the structure;

Figure 5 is a longitudinal sectional view, taken approximately along the line 5—5, Figure 4;

Figure 6 is a vertical sectional view of the structure, taken approximately along the line 6—6, Figure 2;

Figure 7 is an enlarged fragmentary detail elevational view of the front-frame carriage and locking means of the structure;

Figure 8 is a sectional view of the carriage and locking means of Figure 7, taken approximately along the line 8—8, Figure 7; and

Figure 9 is an enlarged fragmentary broken

view of the structure, showing in detail the main or rear seat-providing frame thereof.

Referring now in more detail and by reference characters to the drawings, which illustrate a preferred embodiment of the present invention, 5 the bleachers or seating-structure includes a main or rear frame which comprises a suitable plurality of oblong-rectangular upstanding panels A each, in turn, formed of a front post 1 preferably of angle section, a post 2 preferably also 10 of angle section disposed in spaced parallel rearward relation to post 1, and top and bottom cross connecting-plates 3, 4, bolted, riveted, welded, or otherwise secured rigidly to the posts 1, 2, which, it will be understood, may be of any desired or 15 required gauge, strength, and height.

In the present instance, there are four of the panels A, which are rigidly tied together in suitably spaced parallel relation by means of a suitable plurality of vertically spaced cross-members 20 5, two thereof here being shown, preferably of channel section securely bolted or otherwise fixed to and upon the rearwardly presented faces of the rear panel-posts 2, as best seen in Figures 1 and 2. It may be here stated that, for purposes presently appearing, the panels A are disposed in pairs, with the flanges of the respective angle-posts 1, 2, of each pair in opposed relation.

In practice, the several connected frame-forming panels A are arranged in contiguity or adjacency to a wall B of the particular enclosure in which the bleachers are to be set up or installed, and to such wall B, the main frame is attached by means of a suitable plurality of bolt-members 6, spacing-washers being preferably interposed, as shown, and the respective posts 2 being suitably longitudinally slotted, as at 8, for accommodating the bolts 6 for facilitating vertical shifting movements of the several connected panels A, all as more fully presently appears.

At its lower end, each panel A has slot-and-pin connection, as at 9, with the upwardly presented legs a of a substantially U-shaped bracket 10, the bight b of which is disposed under the respective upstanding panel A and rigidly and 45 firmly, as by means of lag-screws or the like, secured flatwise to and upon the floor C of the gymnasium, auditorium, or other enclosure in which the bleachers is being installed, and riveted or otherwise fixed on a side face of the 50 lower cross-plate 4 of each respective panel A, is a vertically extending frame c bridged at its upper end by a short cross-angle d for housing a strong compression spring 11, which abuts at its upper end against the angle d and at its lower 55

end against the upper face of the bight *b* of bracket 10.

Thus the several tied together and frame-forming panels A are, as a unit, as substantially a unitary structure, normally yieldingly or resiliently urged vertically upwardly, all also for purposes presently appearing and as best seen in Figures 1, 2, and 9.

Suitably fixed upon the upper end of each panel A, is a horizontally disposed short angle-strip 12, and bolted or otherwise secured to the several strips 12, and flatwise extending transversely over the several panels A, is a top seat-member in the form of a suitably elongated plank or board 13, suitably hingedly connected to the front margin of which, as at 14, to normally depend in front of the respective upper end-portions of the several front panel-posts 1, is a correspondingly elongated face-plate or so-called riser 15, the latter with the seat-member 13 forming the top or upper row of seats Z of the bleachers, and the plate or riser 15 having, for purposes presently appearing, pivotally secured upon its under or rear face, as at 16, a suitable plurality of legs 17 normally releasably retained in folded position, as shown in Figure 1, through end-engagement with suitable spring-clips or the like 18 also mounted on the under or rear face of riser 15.

Extending between, and fixed to, the uprights 1, 2, of each panel A just below the lower margin of the face-plate or riser 15, is a reinforcing cross-rib or angle 19, and extending transversely across, and rigidly secured to, the posts 1 of the several panels A with its one leg e presented forwardly in horizontal alignment with the horizontally presented leg f of the angle 19, as best seen in Figures 1 and 2, is a suitably elongated angle 20.

Preferably each panel A is equipped with a suitably elongated forwardly presented horizontal so-called beam 21 constructed of a section of suitable sheet metal doubled upon itself to include opposed flanges g, g, a double-wall stem or web h, and a longitudinally extending cylindrical portion or bead i for purposes presently appearing, the flanges g, g, at the rear end-portion of the beam 21, being disposed in flatwise engagement with, and suitably, as by bolts, rivets, or the like, fixed to, the registering legs e, f, of the angles 19, 20.

Fixed flatwise upon the flanges g, g, of the respective beams 21 with its inner margin adjacent the transverse angle 20, and extending transversely across the several panels A, is a foot-rest in the form of an elongated board 22 of suitable width, and having its lower margin disposed between, and riveted or otherwise suitably fixed to, the walls of the stem h forwardly of the foot-rest 22, is a double wall upstanding plate 23 having along its upper margin outwardly presented opposed flanges j and along its forward margin outwardly presented opposed flanges k.

Disposed flatwise upon and secured, as by bolts or other suitable means, to the respective flanges j of, and extending transversely with respect to, the several panels A, is a seat-providing plate, plank, or board 24, and similarly secured to the respective front flanges k of, and extending transversely across with respect to, the several panels A, is a second face-plate or riser 25.

It will, of course, be understood in this connection that the several beams 21 will be positioned at such a distance downwardly from the seat-board 13, so that the average individual, when seated upon the board 13, will be able con-

veniently and comfortably to rest his feet upon the beam-supported foot-board 22, and similarly the seat-supporting plate 23 will be spaciously arranged with respect to the first seat-board 13 and the foot-board 22, so as to provide a second row 5 of seats Y suitably in front of, and at a lower elevation than, the first or back row of seats Z, all as best seen in Figure 1.

Having slidable engagement with, and telescopically sleeved upon, each respective bead i, 10 is a co-operative so-called bracket 26, forming preferably an integral part of which is an inverted U-shaped clip 26' fitting over, and riveted or otherwise fixed to and upon, the upper end of an upright movable post or standard 27 constructed preferably, as best seen in Figure 5, of a pair of channel-members r, r', disposed and fixed permanently together in back-to-back relation, the several posts 27 of the bleachers being suitably, as by a suitably positioned transverse or 20 cross-member 28, secured or tied together in frame-formation for movement as a unit.

At its lower extremity, each of the posts or uprights 27 has suitably fixed thereto, as best seen in Figure 4, a small flat plate 29 for floor engagement and is mounted for vertically shiftable movement in a carriage D comprising a pair of companion plates 30 suitably secured together in spaced parallel relation by means of cross-braces 31, the plates 30 being converged and extended rearwardly, as at 30', for journal-engagement with a suitable roller 32, and being likewise converged and extended forwardly, as at 30'', for journal-engagement with a second roller 33.

Bolted or otherwise fixed upon the forward face of the forwardly presented flanges of each post or member 27, is a suitable L-shaped bracket 34 for superjacent abutting engagement with a compression spring 35 vertically mounted within 40 the forward portion of the carriage D for subjacent abutting engagement with an opposed companion L-shaped bracket 36 fixed, in turn, upon the forwardly presented face of the adjacent cross-brace 31, as best seen in Figures 4 45 and 5. Thus the several tied together posts or uprights 27 are, likewise as a unit or a unitary frame, normally yieldingly or resiliently urged vertically upwardly and also shiftable laterally with respect to the main or rear frame of the 50 bleachers provided by the several connected panels A. As shown, for facilitating such lateral shiftable movement, the rollers 32, 33, of each carriage D are preferably in tandem relation, while the spaced braces 31 function also as guides 55 for the respective post 27 in its vertically disposed movements. And it may here be stated that the plate forward continuations or extensions 30'' are preferably greatly elongated with respect to the rearward continuations 30' for 60 stabilizing the posts 27 both when in stationary position and when being shifted laterally toward and from the rear panels A.

Bolted or otherwise suitably secured to the respective forwardly presented vertical faces of, 65 and extending transversely across, the several uprights 27, is a cross-rib or angle 28' corresponding both in relative position and purpose to the cross-angle 20 of the row of seats Z, and suitably fixed to, and projecting in spaced parallel relation forwardly from, the angle 28', is a series of beams 21' similar in form and function to the beams 21 previously described, and being likewise provided with a correspondingly positioned transversely-extending foot-board 22' and 75

a series of upstanding flanged seat-supporting plates 23', the latter being, in turn, similar to the plates 23 and similarly equipped with a transversely extending seat-board 24' and face-plate or riser 25'. The beams 21' are also of the same length as the beams 21, and the vertical distance between the beams 21' and the board 24 of the second row of seats Y is equal to the distance between the beams 21 and the seat-board 13 of the first row of seats Z, so that the member 22' provides a foot-rest for use by the occupants of the second row of seats Y, while, at the same time, the supported transverse members 24', 25', form and provide a third row of seats X, which is similarly positioned downwardly and spaced forwardly from the second row of seats Y the same distance as the second row of seats Y is positioned and spaced with respect to the first row of seats Z. Further, the vertical distance between the upper face of the seat-providing member 24' and the beams 21' is equal to the vertical distance between the beams 21' and the lower margin of the face-plate 25, and the several posts 27 are likewise disposed in pairs, the posts 27 of each respective pair thereof, however, being spaced somewhat less than the spacing between the panels A of each respective pair thereof, so that the pairs of standards or posts 27, when the row of seats X is shifted rearwardly, are properly aligned for "nesting" relation with respect to the panels A. Any such movement of the row of seats X is conveniently facilitated by the rollable carriages D and the telescopic or slideable connection between the sleeves 26 and the beams 21, and in any such movement, the beams 21' and their associated foot-board 22' and seat-board 24' will move rearwardly with the uprights or posts 27, thus bringing the seat-board 24' vertically beneath the seat-board 24 and the face-plate or riser 25' in approximately vertical alignment with the first or fixed face-plate or riser 25 in the formation of a substantially unitary wall, as best seen in Figure 2.

Mounted for slideable movement longitudinally on the respective beams 21', are sleeve-brackets 26a similar in form and function to the bracket 26 and each likewise having an inverted U-shaped clip 26' for rigid connection with a second forwardly disposed series of transversely aligned movable uprights or posts 27' similar in form and function, but correspondingly shorter, than the first set of movable uprights or posts 27. The respective posts 27' are likewise mounted for vertically shiftable and laterally traveling movement within roller carriages D', the latter also similar in form and construction to the roller carriages D and the posts 27' being tied together in frame-formation by a cross-angle 28' for unitary movement. The uprights 27' are, in turn, provided with respective horizontally disposed rigid beams 21'' supporting, in like manner as described in connection with the beams 21 and 21', a foot-rest 22'' for the third row of seats X and also a seat-providing board 24'' and a face-plate or riser 25'', thus providing a fourth forwardly and downwardly spaced row of vertically shiftable and laterally movable seats W, a fifth row of also vertically shiftable and laterally movable seats V being in like manner arranged in front of, and, in turn, downwardly spaced from, the row W. It will, of course, be understood that the uprights or posts 27, 27', and so on of the several seat-rows become progressively shorter, as is shown in Figure 1, and that the spacing of the uprights or posts 27' of each pair thereof of the forward

rows X, W, and V is for nesting co-operation successively less, as best seen in Figure 6. And it will further be understood that the bleachers, depending on the original height of the rear wall mounting frame formed and provided by the several connected panels A, may comprise any desired number of rows or tiers of seats. However, for purposes of illustration, we here show a seating-structure or bleachers of our invention comprising merely six rows or tiers of seats; hence the last mentioned row or tier of seats V will, in such installation and as here shown, constitute the second tier of seats from the bottom.

Accordingly brackets 26b sleeved for movement on the associated beams 21b, in all such respects similar to the described brackets 26 and 26a and beams 21, 21', are fixed upon respective relatively short uprights or posts 27b, each having at its lower extremity a floor-engaging plate 29b.

Suitably fixed upon the forwardly presented face of each of the respective posts or uprights 27b, is an inverted U-shaped carriage-frame D'' comprising a pair of opposed companion or registering angle-members m, m, suitably shaped to include front and rear vertical legs 37, 38, respectively, and a horizontally extending bight portion 39.

Pivottally attached, as at n, at its one extremity to and intermediate the angle-members m and extending horizontally rearwardly from the frame-front leg 37, is a suitable mounting 40 shaped in plan as best seen in Figure 8, supporting intermediate its ends for rollable movement in a vertical plane a suitable roller 41. Fastened at its lower end, as at 42, to the rear extremity of the mounting 40 and having slot-and-pin connection, as at 43, with the frame-bight 39, is an upstanding rod 44, coiled upon which and at its opposite ends abutting the upper horizontal face of the roller-mounting 40 and the under face of the frame-bight 39, is a coiled compression spring 45.

As best seen in Figure 1, the rear leg 38 of the frame D'' is similarly provided with a like yielding or spring-urged mounting 40 and roller 41, 45 and tying the several posts 27b together in frame-formation, is a cross-angle 20b. Thus the posts 27b are capable, as a unit, of both vertically yielding and laterally traveling movement.

Bolted or otherwise fixed to and upon the upper face of, and extending transversely across, the horizontal bight-members 39 of the several carriages D'', is a foot-rest 22b similar in all respects to the foot-rests 22, 22', and 22'', the respective carriages D'' being also provided with transversely aligned upstanding seat-supporting plates 23b similar in all respects to the seat-supporting plates 23, 23', and having bolted thereacross a seat-board 24b providing a lower row or tier of seats U.

Hingedly fastened, as at 46, to and beneath the forward margin of the seat-board 24b, is a swingable normally depending face-plate 47 provided preferably centrally of its length with a hand-grip aperture 48, for purposes presently more fully appearing and as best seen in Figures 1, 3, and 7.

Fixed preferably upon each of the outer or end carriage-frames D'', is lock mechanism E comprising a shell-like bracket or housing having a front wall 49 and preferably integral horizontal upper and lower walls 50, 51, respectively, the latter being formed with vertically aligned apertures for slidably accommodating a vertically disposed bolt-member 52, fixed upon which, as 75

by a set-screw 53, midway of its length, is a barrel 54 having a forwardly presented recess or socket 55 for embracingly engaging a rearwardly extending pin 56 eccentrically mounted in cam-like manner upon a disk 57 formed upon the inner end of a short spindle 58 suitably journaled in a bearing 59 provided on the housing front wall 49. As best seen in Figures 1 and 7, the spindle 58 is accessively positioned within an aperture 60 formed in the swingable face-plate 47 and is provided with a diametrical pin 61 for engagement in end-slots of a removable socketed turning-handle 62.

In installing the present bleachers, the concrete or other floor C of the particular enclosure is provided with a pair of transversely aligned recesses 63 so located with respect to the wall B that the bolts 52 of the locks E will be positioned thereabove when the particular bleachers are in fully opened or operative seating position. Thus, to secure the bleachers in such condition and against unauthorized telescoping or folding movement, the socketed handle 62 is inserted in the aperture 60 and engaged with the pin 61 of the spindle 58. Upon turning movement of the handle 62, the spindle 58 will be axially rotated with its eccentric pin or stud 56 and, by reason of its described engagement with the barrel 54, effect vertical movement of the bolt 52. Thus the bolt 52 may selectively be either shifted downwardly into, or upwardly out of engagement with the floor recesses 63, all as best seen in Figure 1.

As has been above stated, the various or several successive sections of the bleachers are of similar size and are positioned relatively at like distances from each other. Thus, when the bleachers are in telescoped or closed position, each of the successive tiers or rows of seats U, V, W, X, Y, will be positioned in vertical registration one beneath the other, the several face-plates or risers 25, 25', 47, will be edgewise vertically aligned in the formation of a substantially solid closed front, as best seen in Figures 2 and 3, and the several panels A will, transversely of the structure, be in alignment, as shown in Figure 6, adding greatly to the stability of the structure when collapsed or folded.

Since the uppermost tier or row of seats Z provided by the seat-board 13 is in fixed rearwardly spaced relation to the next tier or row of seats Y, such intervening space may now be covered by swinging the hinged face-plate 15 outwardly and upwardly and the legs 17 downwardly to endwise rest in vertical plate-supporting position upon the adjacent foot-board 22, as shown in dotted lines in Figure 2, the top closure of such space being augmented by a substantially L-shaped member 64 fixed at its foot, as at 64', to and upon, and extending transversely over, the beams 21 of the several panels A adjacent the rear margin of the seat-board 24, as best seen in Figures 1 and 2.

Thus, in a gymnasium or similar enclosure, basket-balls, indoor baseballs, and the like, if accidentally thrown up against the folded or closed seats, will be deflected backwardly into the playing area, loss of time in recovering the ball or the like from the closed stand being hence eliminated. As shown, the floor C is provided in suitable adjacency to the wall B with a second set of recesses or sockets 63' for co-operative engagement with the bolts 52 for releasably securing the bleachers or stand in fully closed condition.

When it is desired to open the stand or bleach-

ers for accommodation of an audience, spectators, or the like, the locks E are actuated to withdraw the bolts 52 from floor-engagement and the hinged bottom face-plate 47 gripped at the opening 48 and swung outwardly and upwardly in the provision of a pull-handle. The lowest tier or row of seats U is then shifted forwardly into extended position until the several brackets 26b, sliding in such movement on the beams 21b, engage the flanges k of the plate 23' of the next tier V, whereupon continued pulling movement will cause the second tier V to move outwardly and forwardly, and subsequently and in a similar manner the third, and then the fourth row, until the entire stand is in fully opened or operative seating position, as shown in Figure 1. The locks E may thereupon be actuated to shift the bolts 52 downwardly into floor-engagement, so as to prevent any unauthorized retrogressive movement of the stand.

The outward and inward or lateral traveling movements of the various telescoping sections of the structure require comparatively little effort, since, the entire weight of the stand being normally lifted up off of the floor by means of the yielding mountings provided by the springs 11, 35, 45, previously described, such sections are freely and conveniently movable on and with the several roller-carriages D, D', D''. When, however, spectators take their place upon the opened structure, their additional weight will cause the several tiers or rows of seats to move downwardly in unison against the action of the several sets of springs 11, 35, 45, until the several bottom plates 29, 29b, of the movable sections and the panels A of the stationary or rear section rest solidly upon the floor C, with the result that the weight of the loaded structure will be removed from the several carriages D, D', D'', and directly transmitted through the panels A and several sets of uprights 21, 21', 21b to the floor C. Hence, the bleachers or structure, when loaded, is strong, rigid, and immovable, and when not loaded will be freely supported upon the several roller carriages, so that the stand may be closed or opened with a minimum of physical effort, vertical movement of the stationary main or rear frame being freely permitted by reason of its described slot-and-pinion connection with the wall B and the fixed floor-engaging brackets 10.

Preferably, as shown, each of the intermediate frame-uprights 27, 27', is re-enforced or braced by a relatively short channel-member 65, and it is to be understood that the several rows of seats of the structure may be longitudinally elongated to meet the requirements of any particular installation by the inclusion of additional sets or pairs of panels, uprights, and associated members and parts, that the several members of the structure may be additionally re-enforced or braced for strength and rigidity as may be required, and that other changes and modifications in the form, construction, arrangement, and combination of the several parts of the stand or bleachers may be made and substituted for those herein shown and described without departing from the nature and principle of our invention.

Having thus described our invention, what we claim and desire to secure by Letters Patent is,

1. In a foldable seating-structure, a main frame and a plurality of second frames each including uprights spaced transversely of the structure normally elevated from, and vertically yieldable for endwise resting under load upon, a

support, the uprights of the respective second frames being differently spaced and each of said second frames also including a seat-member extending transversely of the structure outwardly beyond the respective uprights thereof, said main and second frames being shiftably interconnected and relatively sized and arranged for mutually nested interfitting relationship when the structure is folded and said seat-members being approximately of equal length and disposed in a stepped series when the structure is unfolded and in vertical registration when the structure is folded.

2. In a foldable seating-structure, a main frame and a plurality of second frames each including uprights spaced transversely of the structure normally elevated from, and vertically yieldable for endwise resting under load upon, a support, the uprights of the respective second frames being differently spaced and each of said second frames also including seat and foot members extending transversely of the structure outwardly beyond the respective uprights thereof, said main and second frames being shiftably interconnected and relatively sized and arranged for mutually nested interfitting relationship when the structure is folded and said seat and foot members being approximately of equal length and disposed in respective stepped series when the structure is unfolded and in respective vertical registration when the structure is folded.

3. A foldable seating-structure comprising, in combination, a main stationary upstanding frame, a pair of spaced parallel seat-providing members disposed at different elevations on said frame, a plurality of upstanding second frames, seat-providing members mounted on each of said second frames, and foot-rest-providing members mounted on some of said frames for co-operative association with the next succeeding seat-member, said second frames being shiftably interconnected one with the other and with the main frame and relatively sized and arranged when folded for nesting one within the other and within, and under the seat-members of, the main frame and the seat-members of said second frames, when the structure is unfolded, being disposed in spaced parallel relation one in front of, and at different lower elevations from, the other and the seat-members of the main frame.

4. A foldable seating-structure comprising, in combination, a main frame for connection to the floor of an enclosure, said frame including a pair of parallel rows of seats spaced downwardly and forwardly one from the other, a plurality of second frames, one of said second frames having connection for shiftable movement with the main frame and the remaining second frames having connection for shiftable movement one with the other, a row of seats supported by each of said second frames, said additional rows of seats being spaced downwardly and forwardly one from the other and from said main seat-rows when the structure is unfolded, and means including respective roller-carriages for supporting the second frames for traveling movement relatively to the main frame and to each other, said second frames being sized relatively to the main frame and one with the other for nesting one within the other and within the main frame and said additional seat-rows being in vertical registration with the lower seat-row of the main frame when the structure is folded.

5. In a seating-structure, in combination with the floor and wall of an enclosure, a U-shaped

bracket having a bight for flatwise disposition upon the floor, the bracket having its legs presented upwardly, a seat-supporting panel including an upright upstanding from the bracket and having slot-and-pin connection for shiftable movement with the wall and the legs of the bracket, and means including a spring interposed between the upright and bracket for supporting the panel yieldingly for endwise resting under load upon the bracket-bight.

6. A foldable seating-structure comprising a main frame having a plurality of transversely aligned uprights and a plurality of forwardly extending transversely aligned horizontal beams fixed to said uprights, first seat-forming means mounted upon and extending transversely across said uprights, second seat-forming means mounted on, and extending transversely across, said beams, a plurality of separate second frames each including a series of transversely aligned and connected uprights and associated horizontal beams fixed to, and disposed inwardly of, the last-named uprights, one of said second frames having sleeve-connection for slidable movement upon the beams of the main frame and the remaining second frames having, in turn, successive sleeve-connections for slidable movement on the beams of the respective preceding frame, and seat-forming means mounted on and for movement with the respective second frames.

7. A foldable seating-structure comprising a main frame having a plurality of transversely aligned uprights and a plurality of forwardly extending transversely aligned horizontal beams fixed to, and disposed inwardly from, said uprights, said frame being normally elevated from, and vertically yieldable for resting under load upon, a floor, first seat-forming means mounted upon and extending transversely across said uprights, second seat-forming means mounted on, and extending transversely across, said beams, a plurality of separate second frames each including a series of transversely aligned and connected uprights and associated horizontal beams fixed to, and disposed inwardly of, the last-named uprights, one of said second frames having sleeve-connection for slidable movement upon the beam of the main frame and the remaining second frames having, in turn, successive sleeve-connection for slidable movement on the beams of the respective preceding frame, seat-forming means mounted on and for movement with the respective second frames, and a roller-carriage at the lower extremity of each of the respective second uprights having spring-means for yieldingly supporting the second frames in normal elevated position from, and for endwise resting under load upon, the floor and for movement over the floor relatively to the main frame.

8. A seating-structure comprising, in combination, a main frame including a pair of parallel rows of seats spaced downwardly and forwardly one from the other, and a hinged plate for selectively forming a riser for one of said rows or a cover for the space intermediate said rows.

9. A seating-structure comprising, in combination, a main frame including a pair of parallel rows of seats spaced downwardly and forwardly one from the other, and a plate hinged to the rear row for selectively forming a riser for said row or an oblique cover for the space intermediate said rows.

10. In a seating-structure, a seat-member supporting-upright, a frame loosely embracing the lower end-portion of the upright, means yieldingly

connecting the upright to the frame, and means for rollably supporting the frame.

11. In a seating-structure, a seat-member supporting-upright, a frame loosely embracing the lower end-portion of the upright, means including a spring having connection with the upright and the frame for supporting the upright yielding relatively to the frame, and supporting-rollers journaled for rotation in the frame.

10 12. In a seating-structure, a seat-member supporting-upright, a frame loosely embracing the lower end-portion of the upright, means including a spring having connection with the upright and the frame for supporting the upright yielding relatively to the frame, and supporting-rollers in tandem relation journaled for rotation in the frame.

20 13. In a seating-structure, a seat-member supporting-upright, a frame loosely embracing the lower end-portion of the upright, means including a spring having connection with the upright and the frame for supporting the upright yielding relatively to the frame, opposed forward and rear extensions on said frame, and tandem rollers journaled for rotation in said extensions, the forward extension being elongated with respect to the rear extension.

30 14. In a seating-structure, a seat-providing panel including an upright, and roller carriage means for operatively supporting said upright at its lower extremity, said means comprising a pair of spaced parallel plates, and a pair of spaced peripherally aligned rollers operatively mounted between the plates, said plates being provided intermediate the rollers with guide means for shiftably receiving the upright.

40 15. A foldable seating-structure comprising a main frame and a plurality of second frames shiftably connected for folding and unfolding longitudinally of the structure, each frame having spaced uprights and the uprights of the several second frames being differently spaced transversely of the structure, and seat-members of approximate equal length transversely of the structure on said second frames disposed in stepped relation one in advance of the other when the structure is unfolded, said seat-members extending transversely of the structure outwardly beyond the respective pairs of uprights and being in vertical registration and said uprights being in lateral registration when the structure is folded.

50 16. A foldable seating-structure comprising a main frame and a plurality of second frames shiftably connected for folding and unfolding longitudinally of the structure, and seat and foot-rest members of approximate equal length transversely of the structure on said second frames disposed in respective vertically registering series when the structure is folded and in respective stepped series when the structure is unfolded, the second frames each including spaced uprights and the uprights of said second frames being differently spaced transversely of the structure, the seat and foot-rest members extending transversely of the structure outwardly beyond the uprights of the respective second frames and said uprights being in registration transversely of the structure when the structure is folded.

60 17. A foldable seating-structure comprising a main frame and a plurality of second frames shiftably connected for folding and unfolding longitudinally of the structure, and seat-risers of approximate equal length transversely of the

structure on said second frames disposed edge-wise in vertical registration when the structure is folded and in stepped series when the structure is unfolded, the second frames each including spaced uprights and the uprights of said second frames being differently spaced transversely of the structure, the seat-risers extending transversely of the structure outwardly beyond the uprights of the respective second frames and said uprights being in registration transversely of the structure when the structure is folded.

10 18. A foldable seating-structure comprising a plurality of frames, seat-members on said frames of approximate equal length transversely of the structure and means including sets of forwardly projecting rigid slidably co-operative members connecting the frames for folding and unfolding.

20 19. A foldable seating-structure comprising a plurality of upright frames, and means connecting said frames for folding and unfolding, said means including rigid beams forwardly projecting horizontally from one of said frames, and co-operative members fixed on the other frame having slidable engagement with said beams.

25 20. A foldable seating-structure comprising a plurality of upright frames, and means connecting said frames for folding and unfolding, said means including rigid beams projecting horizontally from one of said frames, and tubular members fixed on the other frame having sleeve-engagement with said beams for telescopically slidable movement.

30 21. A foldable seating-structure of bleacher type comprising a main row and a plurality of second rows of seats, each second row including a seat-member and uprights, the uprights of the several respective rows being differently spaced transversely of the structure and the seat-members extending transversely of the structure beyond the uprights of the respective second rows, said rows being connected shiftably one with the other for foldable movement longitudinally of the structure and disposed in a spaced stepped series one in advance of the other when the structure is unfolded, said seat members being in nested vertical registration one beneath the other and said uprights being in registration transversely of the structure when the structure is folded.

35 22. A foldable seating-structure of bleacher type comprising a main row and a plurality of second rows of seats, each row including uprights differently spaced transversely of the structure and vertically yieldable for endwise resting under load upon a support, each of said second rows also including a seat-member and said seat-members extending transversely of the structure outwardly beyond the uprights of the respective second rows, said rows being connected one with the other for foldable movement and disposed in a spaced stepped series one in advance of the other when the structure is unfolded, said seat members being in nested vertical registration one beneath the other and said uprights being in registration transversely of the structure when the structure is folded.

40 23. A foldable seating-structure of bleacher type comprising, in combination, a main frame and a plurality of second frames, each frame including uprights spaced transversely of the structure and the uprights of the several second frames being differently spaced, means slidably connecting the second frames one with the other and with the main frame for foldable movement, and

5 seat-members on said frames of approximate equal length transversely of the structure, the seat-members of the second frames extending transversely of the structure outwardly beyond the respective uprights thereof, said frames and seat-members being in respective stepped series one in advance of the other when the structure is unfolded, the seat-members being in nested vertical registration one beneath the other, and 10 said uprights being in registration transversely of the structure when the structure is folded.

15 24. A foldable seating-structure of bleacher type comprising a main row and a plurality of second rows of seats, each row including uprights spaced transversely of the structure and the uprights of the respective second rows being differently spaced, said rows being shiftably connected one with the other for foldable movement longitudinally of the structure and disposed in a 20 spaced stepped series one in advance of the other when the structure is unfolded, the second rows each also including a seat-member and said seat-members extending transversely of the structure outwardly beyond the uprights of the respective second rows, said seat members being in nested vertical registration one beneath the other and said uprights being in registration transversely of the structure when the structure is folded, and means operatively associated and 25 30 movable with one of said second rows for selectively securing all of said rows in unfolded or folded relation.

35 25. A foldable seating-structure of bleacher type comprising a main row and a plurality of second rows of seats, each row including uprights spaced transversely of the structure and the uprights of the respective second rows being differently spaced, said rows being shiftably connected one with the other for foldable movement longitudinally of the structure and disposed in a 40 spaced stepped series one in advance of the other when the structure is unfolded, the second rows each also including a seat-member and said seat-members extending transversely of the structure outwardly beyond the uprights of the respective second rows, said seat members being in nested vertical registration one beneath the other and said uprights being in registration transversely of the structure when the structure is folded, and means including locking bolts carried by one 45 50 of said second rows and endwise shiftable for selectively securing all of the rows in unfolded or folded relation.

55 26. A foldable seating-structure of bleacher type comprising, in combination, a main frame and a plurality of second frames shiftably connected for folding and unfolding longitudinally of the structure, each frame having spaced uprights, seat-members on the second frames of approximate equal length and extending transversely of the structure outwardly beyond the respective uprights thereof, said seat-members being disposed in a stepped series one in advance of the other when the structure is unfolded, said 60 65 seat-members being in vertical registration and said uprights being in lateral registration when the structure is folded, and means comprising roller-carriages for rollably supporting the second frames for movement relatively to the main frame during folding and unfolding of the structure.

70 27. A foldable seating-structure of bleacher type comprising, in combination, a stationary main frame having spaced uprights, a plurality of movable second frames each also including

spaced uprights, and one of said second frames having shiftable connection with the main frame and the remaining second frames having shiftable connection one with the other for folding and unfolding, seat-members on the second 5 frames of approximate equal length and extending transversely of the structure outwardly beyond the respective uprights thereof, said seat-members being in a stepped series one in advance of the other when the structure is unfolded, said 10 seat-members being in vertical registration and said uprights being in lateral registration when the structure is folded, and means including respective roller-carriages for rollably supporting the several second frames for movement relatively to each other and to the main frame during folding and unfolding of the structure. 15

28. A foldable seating-structure of bleacher type comprising, in combination, a main upstanding frame including uprights spaced transversely 20 of the structure and normally elevated from, and vertically yieldable for endwise resting under load upon, a support, a plurality of second upstanding frames each including uprights and the uprights of said second frames being differently 25 spaced transversely of the structure, means connecting one of said second frames with the main frame and the several second frames one with the other for foldable movement, seat-members on the second frames of approximate equal length 30 and extending transversely of the structure outwardly beyond the respective uprights thereof, the several seat-members being in a spaced stepped series one in advance of the other when the structure is unfolded and the second frames 35 being in nested relation with the main frame and said uprights being in registration transversely of the structure when the structure is folded, and means including respective roller-carriages and springs for rollably supporting the second frames for movement relatively to the main frame and for yieldingly supporting the uprights of the second frames in normal elevated position from, and for resting under load upon, said support. 40 45

29. A foldable seating-structure of bleacher type comprising, in combination, a main upstanding frame including uprights spaced transversely of the structure and normally elevated from, and vertically yieldable for endwise resting 50 under load upon, a support, a plurality of second upstanding frames each including uprights spaced transversely of the structure, means including rigid members having co-operable sleeve-engagement for interconnecting the several frames for foldable movement, seat-members on the second 55 frames of approximate equal length transversely of the structure, the several seat-members being in a spaced stepped series one in advance of the other when the structure is unfolded and the second frames being in nested relation with the main frame and said uprights being in registration transversely of the structure when the structure is folded, and means including respective roller-carriages and springs for rollably supporting the second frames for movement relatively to the main frame and for yieldingly supporting the uprights of the second frames in normal elevated position from, and for resting under load upon, said support. 60 65 70

30. A foldable seating-structure of bleacher type comprising, in combination, a plurality of upstanding frames each including forwardly presented members, said frames being shiftably interconnected for folding and relatively sized and 75

arranged for nested relation when folded, and seat-members on said frame-members disposed in a stepped series one in advance of the other when the structure is unfolded and in vertical registration when the structure is folded.

31. A foldable seating-structure of bleacher type comprising, in combination, a first frame including a plurality of forwardly presented spaced beams, a second frame including spaced uprights and a plurality of forwardly presented spaced beams fixed to the respective uprights of the frame adjacent the upper end thereof, the uprights of the second frame having connection at their upper end with the respective beams of the first frame for folding movement, and seat-members supported on the beams of the respective frames disposed in a spaced stepped series one in advance of the other when the frames are unfolded and in nested relation one beneath the other when the frames are folded.

32. A foldable seating-structure of bleacher type comprising, in combination, a first frame having a plurality of forwardly presented spaced beams, a plurality of second frames each including spaced uprights and a plurality of forwardly presented spaced beams fixed to the respective uprights of the frame adjacent the upper end thereof, the uprights of one frame having connection at their upper end with the beams of the next rearwardly adjacent frame for folding movement, and seat-members supported on the beams of the respective frames disposed in a spaced stepped series one in advance of the other when the frames are unfolded and in nested registration one beneath the other when the frames are folded.

33. A foldable seating-structure of bleacher type comprising, in combination, a first frame having a plurality of forwardly presented spaced beams, a plurality of second frames each including spaced uprights and a plurality of forwardly presented spaced beams fixed to the respective uprights of the frame adjacent the upper end thereof, the uprights of the several frames being vertically yieldable for endwise resting under load upon a support and the uprights of one frame having connection at their upper end with the

beams of the next rearwardly adjacent frame for folding movement, and seat-members supported on the beams of the respective frames disposed in a spaced stepped series one in advance of the other when the frames are unfolded and in nested vertical registration when the frames are folded.

34. A foldable seating-structure of bleacher type comprising, in combination, a plurality of upstanding frames each including forwardly presented seat-supporting members, said frames being shiftably interconnected for folding and being relatively sized and arranged for nested relation when folded.

35. A foldable seating-structure of bleacher type comprising, in combination, a plurality of upstanding frames each including forwardly presented seat-supporting beams, said frames having 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300
